DECALCOMANIA

Clarence B. Wilkerson, Chicago, Ill., assignor, by
mesne assignments, of one-half to Davis,
Lindsey, Smith & Shouts, Chicago, Ill., a partnership

Application January 19, 1940, Serial No. 314,691

15 Claims. (Cl. 41—33)

My invention relates to decalcomanias and method of making the same.

One of the objects of my invention is to provide an improved, decorative decalcomania which has a so-called flocked surface, which is of a simple form, may be easily, cheaply and quickly made, may be easily and quickly applied, and which serves its intended purpose in a highly efficient manner.

Another object is to provide a transferable decalcomania by which anything of animate or inanimate nature capable of illustrative reproduction may be realistically reproduced illustratively with respect to form, color, dress and other distinguishing design characteristics.

A further object is to provide a decalcomania including a floc material colored in such a manner as to produce a third-dimensional effect with certain of the design surfaces thereof standing out in relief.

Still another object is to provide a decalcomania having a flocked surface of such character that color, shape, line and other characteristics of the completed design and the component parts thereof are produced by the application of coatings of colored lacquer or like material to the flocked surface after application of the latter.

A further object is to provide a decalcomania having a flocked surface treated in such a manner that the surface appearance or texture of various objects is capable of being reproduced in a realistic manner.

Another object is to provide a decalcomania adapted for ornamentation purposes and having a flocked surface of such character that various colors and color combinations may be applied thereto in the formation of the decalcomania design by overlapping color film surfaces, thereby producing various color effects including blends, tints, shadows and high lights that are highly desirable for realistic reproduction.

An additional object is to provide the foregoing color features by applying a translucent dyed lacquer or the like material of varying colors to component and preshaped parts or areas of the flocked surface with certain of the coatings overlapping at least in part.

Other objects are to provide a simple, efficient and inexpensive method of making a flocked decalcomania and by which all of the foregoing features and advantages may be realized; to provide a method of making a decalcomania of the foregoing character wherein uncolored floc material is applied throughout the surface of the decalcomania design surface and definitely segre-

gated areas thereof are separately colored by a dyed lacquer or like material of such character that different color schemes may be provided by merely overlapping color areas in appropriate sequence; to provide a method of the foregoing character by which the dye material may be effectively applied to segregated parts of the flocked surface without crossbleeding of the material of one surface into another surface; and to provide a method by which all of the color schemes are accomplished in accordance with established color derivation practice by merely overlapping color areas, permitting the dye materials of such overlapping areas to blend together and produce color, similarly, in effect only, to the mixing of materials to produce color.

Other objects and advantages will become apparent as this description progresses and by reference to the drawings, wherein—

20 Figures 1 to 5, inclusive, are top plan views illustrating successive steps of making a decalcomania in accordance with my invention; and

Fig. 6 is an enlarged, transverse, sectional view of the finished decalcomania shown in Fig. 5, the size and thickness of various parts thereof being exaggerated to facilitate explanation of my invention.

In carrying out my invention, the design to be transferred is mounted upon an ordinary piece 30 of decalcomania paper which is provided with an adhesive surface. This adhesive, preferably, takes the form of a glue soluble in water and, as is well known, the decalcomania is detachable by merely wetting through the paper and releasing 35 the adhesive surface so that the transfer design may be slid therefrom.

After selecting a properly sized piece of decalcomania paper I apply to the adhesive surface thereof, preferably by the silk screen stencil 40 method, a coating of clear lacquer or the like material, which coating has the general, and somewhat larger, outline shape of the decalcomania design to be formed. This material, preferably, takes the form of a nitrocellulose or cellulose acetate lacquer having therein a plasticizer approximating ten to fifteen per cent by volume. Other materials such as various kinds 45 of decalcomania varnish may be employed so long as they meet the requirements herein set forth. The plasticizer may take the form of glycerine, castor-oil or any other well known form of material adapted to control the flowability of the lacquer as well as its plasticity in the finished product to prevent cracking and the 55 like. This material which serves as a carrier film

for the remainder of the decalcomania design is insoluble in water and will tenaciously adhere to the adhesive surface of the paper base. While, as shown in the specific illustration of the drawings, I employ a clear uncolored material for this coating, it is to be understood that such material may be dyed or pigmented where desired, particularly where coloration suitably coincides with the design effects which the user desires to attain.

After the carrier lacquer film has properly set or becomes dry, so to speak, I next apply another lacquer or the like coating which is of pigmented form and which I will refer to as the floc-supporting film. This material preferably takes the form of a white pigmented lacquer, such, for example, as a pigmented nitrocellulose or pigmented cellulose acetate lacquer, the particular material depending upon the character of the material employed for the carrier film. It is desired that this lacquer coating fuse or bond with the carrier film. The floc-supporting film is, preferably, applied by the silk screen stencil method and it follows the exact border outline of the completed decalcomania design in all shape and dimensional respects. I preferably employ a white pigmented coating in this instance since, in carrying out my invention, a normally white, noncolored floc material (which is later colored to produce desired color effects) is preferably applied to the floc-supporting film. However, where the color combinations of the completed design permit, the floc-supporting film may be given color. In other words, the color of the floc-supporting film should be such as to avoid all tendency to destroy or change the color effect sought by giving color to the floc. The lacquer or like material employed for the floc-supporting film should include a plasticizer similar to that of the carrier film, and it is, preferably, given an increased adhesive quality by adding thereto a natural gum (Cumar) or a synthetic gum base of any desired and well known type used for this purpose. While the materials above mentioned are well suited for the floc-supporting film, I may also employ any material having an oil, japan or like base with a white or other suitable pigment therein; or I may employ any synthetic resin material having a white or other pigment therein—all of which materials are bondable or fusible with the material of the carrier film.

While the floc-supporting coating is in a so-called wet, tacky and adhesive condition, a white, preferably, bleached floc material is applied thereto in any well known manner by which the floc-supporting film receives and holds its full capacity of such material. Any excess floc that is applied may be removed in any desired manner such as by bumping, shaking and the like. The floc material is, preferably, of fibrous form, and it may be formed from silk, wool, cotton, rayon or any other material suitable for this purpose. The fibers are, of course, of finely divided form and they will become embedded in and adhere to the floc-supporting coating in a rather compact manner. The length of the floc material may be varied in different designs or in the same design, the effect of which is to give a variable depth effect as may be desired in many instances. This floc material is sometimes referred to as tufting, and it is understood that tufting or any other material of like character, so long as the other characteristics re-

ferred to are present, may serve the purpose of my invention.

After the floc material has been applied, the floc-supporting film is permitted to set or dry or harden, so to speak, and after this has taken place and the excess floc material removed, the white, uncolored flocked surface is ready to receive the color treatment necessary to bring out the various design characteristics thereof.

In coloring the flocked surface, assuming that more than one color is to be applied thereto, defined areas are separately and independently colored, color areas of the same color being treated at one time, and different color areas being treated successively in a predetermined color sequence. The color areas may or may not overlap, dependent upon whether or not color blending or toning or mixing is desired to produce any desired color effect, such as tinting, shading, high lighting, etc.

In applying color to definitely defined areas, I employ the silk screen stencil method, the necessary screen surfaces being initially prepared to have the identical dimensional and shape outline of the design surface to be formed. I have found that best results are attained by employing a silk screen of rather large mesh. For example, a screen varying in size from No. 10 (10,000 mesh per square inch) to No. 6 (3,600 mesh per square inch) may be used. I have practically demonstrated that very excellent results may be attained by using a No. 8 (6,400 mesh per square inch) screen for the color application and it may be understood that such a screen is employed in forming the decalcomania of the drawings. The advantages of using a screen of the foregoing character appears to lie in the fact that it is of sufficient size to permit a substantial part of the fibers of the floc material to project up through the screen interstices when the screen surface is applied to the flocked surface so that each floc fiber or group of fibers so projected positively receives or is smeared with coloring material, the tendency being for the screen surface, in removing the screen, to remove any excess material which, if it should remain, might cause color bleeding that would disturb the desired area segregation of the coloring material. In other words, by employing a screen of the foregoing character, it appears that I am able to apply substantially only the proper amount of coloring material to the floc material by a single pass of an extension device such as the usual squeegee over the screen surface, thereby avoiding a condition of over-saturation of the floc material which would cause the coloring material to run into adjacent flocked design areas.

The coloring material, preferably, takes the form of a so-called dyed lacquer, such as nitrocellulose having added thereto, in a manner well known in this art, a dye material of proper color. Or, if desired, an ethyl cellulose lacquer may be employed with good results. These lacquer materials are insoluble in water, and, whichever I employ, it contains a plasticizer like the carrier and floc-supporting film, and it will fuse or bond with the nitrocellulose or cellulose acetate material of the floc-supporting film.

Lacquer material of the character mentioned is of a translucent nature so that when color areas are superimposed, color effects similar to those attained by mixing various paints and color making materials are provided, whereby the maker of the decalcomania design may with a high degree of accuracy reproduce any par-

ticular color scheme that may be required. While lacquer material is preferable, particularly with respect to the example illustrated in the drawings, it is to be understood that any other suitable varnish or material capable of receiving the dye material and capable of being absorbed by the floc material without bleeding into undesired areas may be employed. Also, in some instances a pigmented material may be substituted for the dyed material—particularly where it is not desired to overlap color areas for color blending purposes.

The lacquer material, or any other material employed, is preferably given a viscous quality, having, preferably, according to the falling ball method, a viscosity of 20 C. P. S. Also, this material is of a quick drying nature and, preferably, is of such character that it will become dry or set within twenty minutes to one hour's time after its application. If the particular material selected for the coloring purpose does not have this characteristic, any suitable and well known quick drying agent usually employed in this field may be added to the lacquer material. This addition may be advisable in some instances where overlapping color areas are employed for color blending purposes. The quick drying capacity of the dyed lacquer is greatly facilitated by the fact that the lacquer as applied to the floc material is spread over an extensive floc surface which is directly exposed to the air. These characteristics insure a lacquer material with reduced wetting properties that will slowly wet and soak into the floc material thereby tending to confine the material to the screen covered floc areas.

By employing a lacquer material having the foregoing characteristics for coloring purposes, I am able to apply the coloring material to definitely defined flocked areas without danger of such material bleeding or soaking into adjacent flocked areas. This result is facilitated by using the silk screen stencil method, and I believe that it is materially aided by using a screen arrangement of the character above noted. In any event, by proceeding in the foregoing manner, I find that each segregated flocked area to be colored receives, upon application of the silk screen, a supply of material adequate to substantially entirely saturate each floc fiber but not to over saturate it. I have further found that an over abundance of material may be applied to the flocked surface without over saturation and without bleeding into adjacent surfaces where a viscous and a rapid drying lacquer is employed, the result being that in employing a lacquer having these latter characteristics a lacquer coating may in effect be built upon the top of the flocked surface in addition to saturation of it, causing certain parts of the surface so treated to stand out in relief. Also, this same result may be attained by the use of floc material embodying fibers of varying length. In any event, by the time the entire design surface is fully colored, the entire effect is of a third-dimensional nature, producing a very beautiful and realistic reproduction.

Now referring to the drawings illustrating one decalcomania formed in accordance with my invention, such decalcomania includes a paper carrier 10 of ordinary wettable form having the usual adhesive surface 10a. The design illustrated takes the form of a plurality of red roses having green stems and leaves supported in close or cluster relation. The first step in forming

this design, as illustrated in Fig. 1, is to apply a carrier film 11 formed of clear nitrocellulose lacquer. Or, if desired, this film may be formed of a cellulose acetate lacquer or any other suitable and well known material employed for carrier films. It will be noted, by referring to Fig. 5 showing the finished design, that the outline of this film follows the general outline of the finished design but it is slightly larger than the same. As soon as the carrier film 11 has set or dried sufficiently, I next apply, in the exact outline dimensions of the completed design, a floc-supporting film 12 of white pigmented nitrocellulose lacquer having the adhesive and other qualities hereinabove referred to. Or, if desired, a cellulose acetate lacquer or any other material having similar characteristics may be employed. The material of the floc-supporting film is bondable or fusible with the carrier film 11 and it provides an opaque background for the floc material (which is also white) which is next added.

Immediately following the application of the floc-supporting film 12, and while it is in a wet, tacky and highly adhesive condition, I apply thereto a white, bleached floc material 13, which material fully covers and is embedded in the film 12. It will be noted that the floc material, when applied, completely fills out the outline shape of the completed design. In this instance, I preferably employ a floc material having fibers of substantially the same length but, as already pointed out, in other designs where variable depth appearance effects are desired, floc material having fibers of different lengths is applied to selected areas of the design. In applying floc material of different fiber lengths, I first, preferably, apply the floc-supporting film to only those areas that are to receive the shortest fibers and then apply the short-fibered floc to the same. As soon as these short-fibered areas are set or dried, so to speak, I next apply the floc-supporting film to the surfaces that are to receive the longer-fibered floc material. In this way, the long and short-fibered material is not mixed but is confined to predetermined areas for the desired depth effects.

After the application of the floc material 13, as illustrated in Fig. 2, and as soon as the floc-supporting coating 12 has fully set or dried, all excess floc material is removed therefrom in any desired manner, and a full-flocked surface is presented for color treatment.

In forming the rose design shown in the drawings, necessary shape characteristics are given to the roses 14, stems 15 and leaves 16 by applying a black lacquer material to color areas 17, 18 and 19, respectively, thereof, as illustrated in Fig. 3. This, as above explained, is accomplished by using a silk screen stencil structure having screen areas corresponding in size, shape and location to the black areas 17, 18 and 19 shown on Fig. 3. In accomplishing the steps shown in Fig. 3, the screen is applied directly upon the flocked surface illustrated in Fig. 2 in such a way that some of the floc fibers tend to project through the screen interstices. To this latter end, I preferably employ a No. 8 screen, which is of sufficient size to permit the action stated. The coloring material takes the form of a nitrocellulose lacquer, which has been dyed black by incorporating therein a suitable dye material. This lacquer is insoluble in water, is fusible and bondable with the floc-supporting film 12, is preferably of the viscosity hereinabove noted, and has the ability to dry within a comparatively short time,

as from twenty minutes' to one hour's time. After the screen has been applied to the flocked surface as stated, the lacquer material is forced or squeezed therethrough in the usual manner to deposit upon the defined areas 17, 18 and 19 only that amount of lacquer necessary to color the areas shown in Fig. 3. In this way, as above explained, only the black areas of Fig. 3 are blackened, the material, for reasons already stated, not spreading to or bleeding into surrounding flocked areas.

As soon as the blackened areas 17, 18 and 19 of Fig. 3 have become set or dry, I next color the roses 14 red, as indicated in Fig. 4, and, in so doing, I complete the outline, color and other design characteristics of the roses. This is accomplished by using the silk screen stencil method in the same manner as explained in connection with the step of Fig. 3, except that the stencil screen surfaces have the outline shape only of the roses 14, and the lacquer material is dyed to the proper red color rather than black. In applying this material, as will be noted in Fig. 4, the red lacquer material, which is also of the nitrocellulose type so that it bonds with the black lacquer material, overlaps in some instances certain parts of the previously applied black lacquer surfaces and particularly those which were applied to the rose surface. In this way, the black surfaces provide an outline and shading effect which gives definite shape and design character to the red colored roses. By the time this step has taken place, the rose takes definite form and becomes a very realistic representation of an actual rose of the color in question.

The final step in the formation of the design in question is illustrated in Fig. 4, where the outlined leaf and stem portions of the design are given a green color. In carrying out this step, I employ a silk screen type of stencil like that used in the previous steps, except that it is provided with screen surfaces corresponding in shape only to the leaf and stem areas. Also, I employ a lacquer material similar to that employed in the previous steps shown in Figs. 3 and 4, except that it is dyed to the proper green color. This lacquer material is applied through the screens in a manner similar to the application of the previous colors after the rose lacquer surfaces have become set or dried, and when the lacquer is so applied, the finished product, as appears in Fig. 5, is produced.

It will be seen from the foregoing that upon the completion of the final step shown in Fig. 5 the decalcomania is complete and ready for transfer as soon as it has become sufficiently dried or cured or set to permit of that. In this respect, a few hours' time may be sufficient in some instances and in other instances a much longer time may be required, dependent upon the character of the materials employed and the use to which the decalcomania is to be put.

The component parts of the completed decalcomania are illustrated in the exaggerated sectional view of Fig. 6. When it is desired to transfer the formed design to any desired surface, whether it be wood, fabric, metal, glass, or what not, it is only necessary to sufficiently wet the paper carrier 10 and its glue surface 10^a to cause it to release the carrier film 11, after which the carrier film with the decalcomania carried thereby may be slid in the usual manner from the paper carrier 10 directly upon the surface intended to receive the same. In so removing it

from the paper 10, the carrier film 11 carries along with it a substantial part of the adhesive from the paper 10 so that, when it is applied to the desired surface and smoothed out thereupon to remove all air bubbles, it will adhere tenaciously similarly to an ordinary decalcomania.

I believe that the operation and advantages of my invention will be obvious from the foregoing description. It will be understood that by first applying the floc material in an uncolored state and then coloring it in place upon the design any desired color effect may be attained. This is accomplished by blending the colors much in the same manner that one may mix different colored paints or liquids by mixing paints or liquids or materials of different colors. For example, the combination of the colors yellow and blue provide a green color; and, by placing blue over yellow, in carrying out my invention, the green resulting has a blue cast, and if yellow is placed over the blue the green resulting has a yellow cast. This same thought is extended to all color combinations. The color blending referred to is accomplished by overlapping color areas and by the bonding and fusing ability with respect to each other of the overlapping dyed lacquer surfaces. Therefore, in carrying out this invention, one is not limited with respect to color possibilities. One is not limited to commercially available colored floc materials which, if that should become necessary, would materially limit and restrict color arrangements. One may actually make his color scheme in making up any particular decalcomania design by mixing or blending his colors as they are applied to the flocked surface, all of which would be impossible if colored floc material were employed. The translucent nature of the dyed lacquer material makes this blending possible but if, as stated hereinabove, blending is not necessary a finely pigmented or opaque lacquer material might be employed. Of course, where a translucent material is employed, the translucency may be varied to give variable color effects. Furthermore, from the foregoing it will be seen that a decalcomania embodying my invention may be made easily and quickly as well as quite inexpensively. The fact that only one application of the floc material is required, the remainder of the operations being merely dyeing operations, greatly facilitates the foregoing. Also, as a result of all the foregoing, the finished product has a third-dimensional effect. It has depth, giving the several parts brought out by color a distinct appearance simulating the natural eye appearance of the object treated. Take the roses and leaves formed, for example, as shown in Fig. 5, they stand out as separate, individual units and their surface appearance closely approaches that of natural roses and leaves.

It is to be further understood that although I have shown only one form of design embodying my invention, it may be practiced in the forming of any desired colored design (black or otherwise), whether the color areas be areas distinctly segregated or arranged in overlapping relation for blending purposes. It is also to be understood that, if desired, the depth of the flocked surface may be increased by superimposing a plurality of layers of floc material. For example, if the depth of two layers is desired, one layer of the floc material may be applied to the floc-supporting film as above explained. The second layer is added by applying to the first

floc surface a floc-supporting material similar to the first-applied floc-supporting film, and, before this latter material dries, the additional layer of floc material is applied similarly to the first layer.

I claim:

1. A decalcomania comprising a carrier member having an adhesive coating soluble in water, a coating of material insoluble in water and of greater outline size than the completed design disposed upon said adhesive coating, said material assuming a flexible film form adapted to serve as a design carrier film, a second coating of material insoluble in water and having the exact outline size and shape of the completed design disposed upon said first coating, said material being bondable with the material of said first coating and having adhesive characteristics in its wet or non-dried condition, a coating of white fibrous floc material adhesively secured throughout said second coating, and means for defining design characteristics within the outline of the completed design including one or more coatings of colored lacquer material on said flocked surface, said latter material being insoluble in water, bondable with said second coating, quick drying and adapted to be absorbed by said floc material at a slow rate, the arrangement being such that the desired design characteristics are provided by variation in the color of said latter material and by overlapping certain of said coatings.

2. A decalcomania comprising a carrier member having an adhesive coating, a lacquer or like coating disposed on said adhesive coating, a second lacquer or like coating disposed on said first lacquer coating bondable therewith and having the exact outline size and shape of the completed design, a coating of white fibrous floc material adhesively secured to and throughout the surface of said second mentioned lacquer coating, and a plurality of lacquer or the like coatings of varying colors disposed upon and absorbed in said floc material in distinctly segregated areas thereof, said variable color coatings providing the shape, line and color characteristics of the completed design.

3. A decalcomania comprising a carrier member having an adhesive coating, a substantially clear lacquer or like coating disposed on said adhesive coating, a white and substantially opaque lacquer or like coating disposed on said first lacquer coating bondable therewith and having the exact outline size and shape of the completed design, a coating of white fibrous floc material adhesively secured to and throughout the surface of said white lacquer coating, and a plurality of lacquer or the like coatings of varying colors disposed upon and absorbed by said floc material in distinctly segregated areas thereof, said variable color coatings providing the shape, line and color characteristics of the completed design.

4. A decalcomania comprising a paper or other suitable carrier member having an adhesive coating soluble in water, a lacquer or like coating insoluble in water disposed on said adhesive coating and adapted to serve as a carrier film for the completed design, a white pigmented lacquer or like coating insoluble in water disposed on and bondable with said carrier film, said white coating having adhesive characteristics and the exact outline size and shape of the completed design, a coating of white fibrous floc material adhesively secured to and throughout the entire surface of

said white coating, and a plurality of dyed lacquer or the like coatings of varying colors, insoluble in water and bondable with said white coating, carried by said floc material in distinctly segregated areas thereof, said variable color coatings providing the shape, line and color characteristics of the design being formed.

5. A decalcomania comprising a paper or the like carrier member having an adhesive coating soluble in water, a clear lacquer or like coating insoluble in water disposed on said adhesive coating and constituting a carrier film of greater outline size than the completed design, a white pigmented opaque lacquer or like coating disposed on said carrier film and constituting a floc-supporting film, said latter film being insoluble in water, being bondable with said carrier film, being adhesive in a nondry condition and being of the exact outline size and shape of the completed design, a white fibrous floc material adhesively secured to and throughout the entire surface of said floc-supporting film, and a plurality of lacquer or the like coatings of varying colors disposed upon and absorbed in said floc material in predetermined area portions thereof, said lacquer coatings being insoluble in water, bondable with said floc-supporting film and capable of drying at a comparatively rapid rate, the arrangement being such that said variable color coatings provide the shape, line and color characteristics of the completed design.

6. A decalcomania comprising a carrier member having an adhesive coating soluble in water, a lacquer or like coating insoluble in water disposed on said adhesive coating and constituting a carrier film for the completed design, a white pigmented lacquer or like coating insoluble in water disposed on and bondable with said carrier film, said white coating having the exact outline size and shape of the completed design, a white fibrous floc material adhesively secured to and throughout the surface of said white coating, and a plurality of translucent, dyed lacquer or the like coatings insoluble in water and of varying colors applied to and absorbed by said floc material in selected areas having the shapes of distinct parts of the completed design, the arrangement being such that said variable color coatings provide the shape, line and color characteristics of the completed design, the translucency of the coating material providing variable color effects by overlapped color areas.

7. A decalcomania comprising a carrier member having an adhesive coating, a lacquer or like coating disposed on said adhesive coating, a white pigmented lacquer or like coating disposed on said first lacquer coating bondable therewith and having the exact outline size and shape of the completed design, a white fibrous floc material adhesively secured to and throughout the surface of said second mentioned lacquer coating, and means for providing finished line, shape and color characteristics in the completed design comprising a plurality of translucent dyed lacquer coatings applied to selected areas of the flocked surface, said areas having the outline shapes of component parts of the completed design and some of said coatings overlapping each other for color control effects.

8. A decalcomania comprising a carrier member having an adhesive coating, a lacquer or like coating disposed on said adhesive coating, another lacquer or like coating disposed on said first lacquer coating bondable therewith and having the exact outline size and shape of the completed

design, white fibrous floc material adhesively secured to and throughout the surface of said second mentioned lacquer coating, and means for providing finished line, shape and color characteristics in the completed design comprising a plurality of translucent dyed lacquer coatings applied to selected areas of the flocked surface, said areas having the outline shapes of component parts of the completed design and some of said coatings overlapping each other for color control effects.

9. A decalcomania comprising a carrier member having an adhesive coating soluble in water, a coating of lacquer or like material insoluble in water disposed upon said adhesive coating and forming a carrier film, a coating of lacquer or like material insoluble in water and constituting a floc-supporting film having adhesive characteristics and bondable with said carrier film disposed upon said carrier film and having the exact outline size and shape of the completed design, white floc material applied to and supported throughout the entire surface of said floc-supporting film, and means giving shape and design characteristics to said flocked surface comprising a lacquer or the like material insoluble in water, bondable with said floc-supporting film and of selected color applied to distinctly segregated floc areas, the design characteristics and segregation of floc areas being provided by applying material of varying colors, said material being absorbed by the floc of said areas.

10. A decalcomania comprising a carrier member having an adhesive coating, a lacquer or the like coating disposed on said adhesive coating, a second lacquer or the like coating disposed on said first lacquer coating, bondable therewith and having the exact outline, size and shape of the completed design, a coating of fibrous floc material adhesively secured to and throughout the surface of said second-mentioned lacquer coating, a coating of lacquer or the like material disposed on said floc coating, another coating of fibrous floc material adhesively secured to said latter-mentioned lacquer coating, and at least one coating of lacquer or the like material of predetermined color disposed upon and absorbed in the latter-applied floc material.

11. A decalcomania comprising a carrier member having an adhesive coating, a lacquer or the like coating disposed on said adhesive coating, a second lacquer or the like coating disposed on said first lacquer coating, bondable therewith and having the exact outline, size and shape of the completed design, a coating of white floc material including comparatively short fibers adhesively secured to and throughout selected portions of the surface of said second-mentioned lacquer coating, a coating of white floc material including longer fibers adhesively secured to and throughout the other areas of the surface of said second-mentioned lacquer coating, and at least one lacquer or the like coating of predetermined color disposed upon and absorbed in said flocked areas.

12. A decalcomania comprising a carrier member having an adhesive coating, a lacquer or the like coating disposed on said adhesive coating, a second lacquer or the like coating disposed on said first lacquer coating, bondable therewith and having the exact outline, size and shape of the completed design, a coating of fibrous floc material adhesively secured to and throughout the surface of said second-mentioned lacquer coating, a coating of lacquer or the like material disposed on said floc coating, another coating of fibrous floc material adhesively secured to said latter-mentioned lacquer coating, and a plurality of lacquer or the like coatings of varying colors disposed upon and absorbed in the floc material of said uppermost layer in distinctly segregated areas thereof, said variable color coatings providing the shape, line and color characteristics of the completed design.
13. A decalcomania comprising a carrier member having an adhesive coating, a lacquer or the like coating disposed on said adhesive coating, a second lacquer or the like coating disposed on said first lacquer coating, bondable therewith and having the exact outline, size and shape of the completed design, a coating of white floc material including comparatively short fibers adhesively secured to and throughout selected portions of the surface of said second-mentioned lacquer coating, a coating of white floc material including longer fibers adhesively secured to and throughout the other areas of the surface of said second-mentioned lacquer coating, and a plurality of lacquer or the like coatings of varying colors disposed upon and absorbed in said floc material in distinctly segregated areas thereof, said variable color coatings providing the shape, line and color characteristics of the completed design.
14. A decalcomania comprising a carrier member having an adhesive coating, a lacquer or like coating overlying said adhesive coating and having substantially the exact outline, size and shape of the completed design, a coating of white fibrous floc material adhesively secured to and throughout the surface of said lacquer coating, and a plurality of lacquer or the like coatings of varying colors disposed upon and absorbed in said floc material in distinctly segregated areas thereof, said variable colored coatings providing the shape, line and color characteristics of the completed design.
15. A decalcomania comprising a carrier member, a lacquer or like coating mounted upon said carrier member and having substantially the exact outline, size and shape of the completed design, a coating of white fibrous floc material adhesively secured to and throughout the surface of said lacquer coating, and a plurality of lacquer or the like coatings of varying colors disposed upon and absorbed in said floc material in distinctly segregated areas thereof, said variable colored coatings providing the shape, line and color characteristics of the completed design.

May 19, 1942.

CLARENCE B. WILKERSON.

It is hereby certified that the name of the assignee in the above numbered patent was erroneously written and printed as "Davis, Lindsey, Smith & Shouts" whereas said name should have been written and printed as --Davis, Lindsey, Smith & Shonts--, as shown by the record of assignments in this office, and that the said Letters Patent should be read with this correction office, and that the same may conform to the record of the case in the Patent Office.

Signed and sealed this 28th day of July, A. D. 1942.

Henry Van Arsdale,
Acting Commissioner of Patents.

(Seal)
